CONDIMENT SHAKER

Paul K. Schilling, 1554 Lincoln Ave., St. Paul, Minn.

Filed June 17, 1963, Ser. No. 75,357

Term of patent 14 years

(Cl. D44—22)

FIG. 1

FIG. 2

FIG. 3

FIG. 4

FIG. 6

FIG. 5

I claim:

The ornamental design for a condiment shaker, as shown.
